ATTORNEY

UNITED STATES PATENT OFFICE

MORRIS KORNBLUM, OF BROOKLYN, NEW YORK, ASSIGNOR TO METAL LAMP CORPORATION, A CORPORATION OF NEW YORK

DESIGN FOR A LAMP

Application filed June 22, 1929. Serial No. 31,803. Term of patent 3½ years.

To all whom it may concern:

Be it known that I, MORRIS KORNBLUM, a citizen of the United States, residing at Brooklyn, in the county of Kings and State of New York, have invented a new, original, and ornamental Design for Lamps, of which the following is a specification, reference being had to the accompanying drawing forming part thereof. An incandescent lamp (not shown) is positioned within the body portion or base so that the light reflected through the mirror will be directed toward the upright mirror and the figure.

The figure is a front view.

I claim:

The ornamental design for a lamp, as shown and described.

MORRIS KORNBLUM.
